INVENTOR.

Thos. J. Price

UNITED STATES PATENT OFFICE.

THOMAS J. PRICE, OF MACOMB, ILLINOIS.

SORGO-EVAPORATOR.

SPECIFICATION forming part of Letters Patent No. 240,543, dated April 26, 1881.

Application filed February 26, 1881. (No model.)

To all whom it may concern:

Be it known that I, THOMAS J. PRICE, of Macomb, in the county of McDonough and State of Illinois, have invented new and useful Improvements in Sorgo-Evaporators, of which the following is a specification, in which—

Figure 1 is a perspective view. Figs. 2, 3, and 4 are detached parts, which will be fully described hereinafter.

10 The novelty of this invention consists, first, in an automatic skimmer provided with suitable mechanism to elevate it in its rearward movement; second, in the combination of all the mechanism for operating the skimmer automatically; third, in the construction of the bottom of evaporator so as to form cross-partitions and the manner of securing them together water-tight without solder; fourth, in an adjustable heat-regulator attached to the 15 under side at the rear of the evaporator to prevent the sirup from scorching while in the last stage of its concentration.

Similar letters refer to like parts in each figure.

20 Figure 1 represents my invention in perspective, in which A represents the skimmer, which is operated by the lever-frame r. c c are the connecting-rods that connect the lever-frame r and the skimmer A together. These 25 rods are rigidly attached to the skimmer-heads b b at the front end. The rear end is loosely attached to the outside at the lower ends of the arms of the lever-frame r. In the rear of the skimmer-heads b b are attached the triggers e e, 30 which are provided with a flat spring, i i. At the lower end of these triggers a shoulder, n, is formed. The springs i i rest at their lower ends against the insides of the rods c c. (See 35 Fig. 3.)

40 In Figs. 1 and 2, a a a represent the partitions, which are made, together with the bottom, of sheet metal, and each section of the bottom is so shaped and bent at each side that when they are joined together, as shown in Fig. 2, one side of the partition at the top turns over the other, which, when milled down firmly, forms a water-tight joint. Between the laps e e is placed a strip of canvas, g, which extends back to and then up between the upturned 45 partitions a a to their upper edge, and when all is riveted solid together it makes the joints water-tight.

The patches J are fitted over the inner end of the overlapping edges e e, to give strength and durability to the joint.

55 B represents, in perspective, (see Fig. 4,) the heat-regulator, which is made of sheet metal, and has at each side upturned flanges, which are provided with a series of slots, s s s. This heat-regulator is fitted to the bottom of the 60 evaporator at the rear end. (Shown in Fig. 1.) The upturned flange y passes up between the two plates that form the partitions a a. The slotted flanges come up outside and are secured to the sides of the evaporator with suitable 65 nails or screws. The slots s s s allow it to be raised or lowered, so as to give the proper degree of heat that may be required to reduce the sirup to its proper density without scorching.

70 Operation: The saccharine juice is first let into the front or cleansing apartment to be defecated and skimmed, and the furnace is so arranged that the ebullition commences first at the partition, which causes the scum and feculent matter to flow forward and settle on the 75 inclined end R. Then the operator takes hold of the handle u and draws back the skimmer A until the triggers e e run into the nicks m m on the sides of the evaporator. (See Fig. 1.) The rear part of these nicks are cut wedge-shaped, and when the skimmer-heads b b are drawn past them they press out the triggers e e, which allows the skimmer to fall down into the juice. The operator then runs the skimmer forward to and up the inclined end R and 80 deposits the scum in the gutter P, and in so doing the skimmer has been elevated sufficient 85 to allow the shoulder n on the trigger e to rise above the upper edge of the sides of the evaporator. The springs i i then press the triggers in and hold that part projecting below the shoulder n against the sides, the shoulder n resting on the upper edge, and consequently 90 when the skimmer A is drawn back for another batch of scum it is again elevated, as shown in Fig. 1, above the accumulating scum. When the juice is thoroughly cleansed the gate d is raised and the juice is let into the back sections, and the water with which they 95 had been previously supplied is let out at the gate o, and the fresh juice is let into the front again, as before, making the operation continuous. When the juice is let into the section between the partitions it travels in a trans-

verse direction, passing through the openings at alternate ends of the partitions *a a a*. In the rear sections, under which the heat-regulator *B* is placed, the sirup is reduced to the proper density required for sirup or sugar, and is let out at the gate *o*.

- Having thus fully described my invention, what I claim, and desire to secure by Letters Patent, is—
- 10 1. A skimmer automatically elevated in its rearward movement by means of the triggers *e e*, substantially as shown and described.
  - 15 2. The skimmer *A*, head-pieces *b b*, triggers *e e*, springs *i i*, and nicks *m m*, in combination with the rods *c c* and lever-frame *r*, all operat-

ing jointly together, as and for the purpose set forth.

3. The arrangement and combination of the overlapping edges *e e*, canvas luting *g*, as described, patches *J*, and partitions *a a a*, formed 20 of two sheets of metal, one turning over the other at the top to form a water-tight joint, arranged substantially as shown and described.

4. The adjustable heat-regulator *B*, constructed substantially as shown and described, 25 for the purpose set forth.

THOS. J. PRICE.
